UNITED STATES PATENT OFFICE.

JOHN A. WILLIAMS, OF BROOKLYN, NEW YORK, ASSIGNOR TO THE WILLIAMS AUTOMATIC MACHINE COMPANY, OF MOUNDSVILLE, WEST VIRGINIA.

VENDING APPARATUS.

SPECIFICATION forming part of Letters Patent No. 430,497, dated June 17, 1890.

Application filed December 4, 1889. Serial No. 332,521. (No model.)

To all whom it may concern:

Be it known that I, JOHN A. WILLIAMS, a citizen of the United States, residing at Brooklyn, in the county of Kings and State of New York, have invented certain new and useful Improvements in Vending Apparatus, of which the following is a specification.

My invention relates to automatic vending-machines, and is designed, primarily, as an improvement upon that for which Letters Patent of the United States No. 402,374 and No. 414,787, bearing date, respectively, April 30, 1889, and November 12, 1889, were issued to me, the primary object of the invention being to prevent the operator from losing the coin in case it should happen that he fails to pull the operating or actuating slide outward the requisite distance.

The invention also embraces other features and details, which will be hereinafter fully set forth and claimed.

In the accompanying drawings, Figure 1 is a bottom plan view of the operating or actuating slide and attendant parts, the delivery-slide being broken away for a portion of its length; Fig. 2, a top plan view of the delivery-slide; Fig. 3, a longitudinal sectional view through the operative parts of the machine, showing the position the parts occupy immediately after the insertion of a coin, the coin being shown in its proper position. Figs. 4, 5, and 6 are transverse sectional views on the lines 10 10, 11 11, and 12 12 of Fig. 1; Fig. 7, a perspective view of the pawl or dog for holding the delivery-slide out until released by the actuating-slide, and also showing the supplemental pawl or arm for holding the operating-slide out in its extended position; Fig. 8, a perspective view of one of the blocks, of

which there are two, used for supporting and holding the coin; Fig. 9, a longitudinal sectional view showing the position the parts occupy after the insertion of a coin and after the operating-slide has started to move; Fig. 10, a similar view showing the position the parts occupy when the operating-slide is extended slightly farther than represented in Fig. 9; Fig. 11, a longitudinal sectional view showing the delivery-slide held in its extended position and the actuating-slide moving inward preparatory to striking the pawl or dog and releasing the delivery-slide; and Fig. 12

is a sectional view illustrating the manner in which washers and similar devices are prevented from actuating the machine.

55

A indicates a supporting-frame for the operating mechanism, which frame in the present instance is shown as made of a single casting. The frame comprises a plate B, having a coin-opening a, a block C, upon which the articles to be sold rest, and parallel walls or guides D, which are grooved on their inner faces to receive the operating-slide E and the delivery-slide F, these parts being arranged substantially as in my former patent, 60 No. 414,787, above referred to.

G indicates a pawl or dog journaled in the guides D and provided with two arms b and c, one b extending upward behind the end of the operating-slide, and the other c being 70 adapted to engage depressions or teeth d, formed in the upper face of the delivery-slide. A spring I, secured at one end to the delivery-slide and at the other end to a plate J or other fixed part of the machine, keeps the 75 said delivery-slide in its proper position, while a spring H, secured to the pawl or dog G and to an arm K upon the under side of the operating-slide, keeps the latter normally within the casing of the machine.

80

The operating-slide E is provided with a coin-slot e, normally in alignment with the coin-slot a in the plate B, and the outer end of said slide E is turned upwardly, so as to form a handle by means of which the slide 85 may be actuated.

Delivery-slide F is provided with an opening f near its front end, and in advance of the opening it is provided with a lug or projection g, as shown in Figs. 2, 3, 5, 6, 9, 10, 90 11, and 12, the said lug or projection being located in advance of the arm K, secured to the under side of the operating-slide.

Pawl or dog G is provided with an arm h, to which is secured a spring arm or pawl I, 95 which normally rests within an opening i, formed in the operating-slide E, as shown in Figs. 1 and 3, the said operating-slide being provided on its under face in rear of the opening or slot i with teeth or notches j, as also 100 shown in Figs. 1, 3, 9, 10, and 11, for a purpose presently explained.

M indicate two blocks which are secured to the inner faces of the walls or guides D in

line with the coin-slot *a*, formed in the plate *B*, each of said blocks being provided with two flanges *k* and *l*, as shown in Figs. 1, 3, 4, 5, 6, 8, 9, 10, 11, and 12. The flanges *k* of one block are arranged directly opposite the flanges *k* of the other block, while the flanges *l* are similarly arranged. It will be noticed upon reference to Figs. 4, 5, 6, and 8 that the faces of the flanges *k* are straight at their upper ends and curved gradually toward each other, while the flanges *l* are straight at their lower edges and curved toward each other at their upper ends, the curvature of the flanges *k* and *l* corresponding exactly to the form of the coin or other device which it is intended shall serve to operate the machine.

Upon reference to Figs. 1 and 3 it will be noticed that the flanges *k* are arranged directly beneath the coin slot or opening *a*, so that when a coin is inserted into the machine and passes through the coin-slots *a* and *e* it will rest upon and be supported at its lower sides by the curved portions of the flanges *k*, the coin being prevented from falling backward by reason of the curved arm *K*, whose forward edge is directly in line with the rear edge of the coin-slot *e*, formed in the operating-slide *E*, as shown in Figs. 1 and 3. When, therefore, a coin of the requisite size is placed in the machine, it will be supported at its lower sides by the curved portions of the flanges *k*, at its rear by the arm *K*, and at its upper edge by the walls of the slot *e*, formed in the operating-slide *E*, and it will also be noticed that when the coin is thus held it will be in position to strike the lug or projection *g*, formed upon the delivery-slide *F*.

The operation of the machine is as follows: Assuming that a coin of the requisite size has been inserted into the machine and occupies the position represented in Fig. 3, a slight pull upon the operating-slide *E* in the direction of the arrow, Fig. 9, will cause the coin to strike the lug or projection *g* upon the forward end of the delivery-slide, and by means of the spring *H*, connecting the operating-slide with the pawl or dog *G*, the latter will be rocked or tipped slightly, so as to throw the spring-arm *L* out of engagement with the operating-slide and throw the arm *c* of the pawl or dog *G* into engagement with the delivery-slide, the latter having been moved sufficiently, by reason of the engagement of the coin with lug *g*, to bring the depression *d* beneath the lower arm *c* of the pawl or dog *G*. Continuing, the outer movement of the slides *E* and *F* causes the lower arm *c* of the pawl or dog *G* to rise out of the depression *d*, thereby throwing the spring arm or pawl *L* upward into engagement with the teeth or notches *j* upon the under side of the delivery-slide; but with the parts in this position it will be seen that the delivery-slide has not been moved outward sufficiently to complete the delivery of the article to be sold. In my former constructions if the operator

should happen to let go of the operating-slide at this point the spring *H* would draw the latter inward and drop the coin into the machine without making any delivery of the articles to be sold; but under the present arrangement should it happen that the operator let go of the operating-slide the latter will be prevented from moving inward by reason of the spring arm or the pawl *L*, which holds the said slide *E* extended, so that by a further and subsequent movement of the actuating-slide the article to be sold may be ejected. It will be seen upon reference to Fig. 10 that the spring arm or pawl *L* not only holds the operating-slide extended, but also holds the coin in engagement with the delivery-slide. Continuing the outward movement of the slides, the second depression *d* will be brought under the arm *c* of the pawl or dog, and the latter will, by reason of the spring *H*, be tipped or rocked, so that its arm *c* will be thrown down into the depression *d*, and, as the arm or pawl *L* is connected with the pawl *G*, the pawl *L* will be thrown out of engagement with the operating-slide, as shown in Fig. 11, in which figure the delivery-slide is shown in the position that it occupies when the delivery of the article has been completed. By releasing the hold upon the operating-slide the spring *H* draws the said slide inward until its inner end strikes the upwardly-projecting arm *b* or the pawl or dog *G*, tipping or rocking said pawl and throwing its lower arm *c* upward out of engagement with the slide *F* and permitting the latter's spring *I* to return it to its normal position indicated in Fig. 3. Upon reference to Fig. 11 it will also be observed that at the moment the operator releases the operating-slide *E* and the latter moves inward there is no longer any support for the rear face of the coin, and the latter, being unsupported, will drop into the receptacle made to receive it. When the spring arm or dog *L* is in engagement with the operating-slide *E*, as indicated in Fig. 10, an inward movement of the operating-slide *E*, as indicated by the dotted arrow in said Fig. 10, will cause said spring-arm to yield and to be thrown out of engagement with the operating-slide, as indicated by dotted lines, the inward movement of the slide releasing the coin and permitting the same to fall into the receptacle provided for that purpose, thereby effectually preventing the surreptitious working of the machine by a rapid reciprocation of the slide *E*. In case a washer, in lieu of a coin, should be placed in the machine, it will be seen, upon reference to Fig. 12, that as the operating-slide *E* is pulled outward and the lower edge of the washer comes in contact with the lug or projection *g* the washer, being unsupported at its back by the arm or finger *G*, will be tipped or rocked and disengaged from the operating-slide, and will consequently fail to connect the slides *E* and *F*. The curved faces of the flanges *k* and *l* form in effect a circular passage-way or opening

through which the coin must pass, and it will be apparent that if the device inserted into the machine be of a larger size than the coin it will not be able to be moved past both sets of flanges *k* and *l*. On the other hand, if the device inserted be smaller than the coin, it will drop down so far that its upper edge will be unsupported, and as soon as the slide *E* is pulled outward the upper end of the device will be tipped or rocked in the same manner, substantially as the washer represented in Fig. 12.

Having thus described my invention, what I claim is—

- 15 1. In a vending-machine, the combination, with a delivery-slide, of an actuating-slide adapted to be connected therewith by means of a coin, and a locking device, substantially such as shown, adapted to engage the actuating-slide, whereby the slides may be held in a partially-extended position.
- 20 2. In a vending-machine, the combination, with a delivery-slide and an operating-slide adapted to be connected by means of a coin, of a yielding locking device for holding the operating-slide in its partially-extended position, but which is adapted to yield upon the inward movement of said operating slide.
- 25 3. In a vending-machine, the combination, with a delivery-slide and an operating-slide adapted to be connected by means of a coin, of a pawl or dog adapted to engage the delivery-slide and a pawl or dog adapted to engage the operating-slide, said pawls alternating in their movements, as and for the purpose set forth.
- 30 4. In a vending-machine, the combination, with an operating-slide, of a delivery-slide adapted to be connected therewith by means of a coin, a pawl *L* normally in engagement with the operating-slide, and a pawl *G*, adapted to be thrown in engagement with the delivery-slide, all substantially as shown, whereby when the pawl *G* is in engagement with the delivery-slide the pawl *L* will be thrown out of engagement with the operating-slide.
- 35 5. In combination with the slide *E*, provided with an opening *i* and teeth *j*, slide *F*, provided with depressions *d*, a rocking pawl or dog *G*, adapted to engage the depressions in the slide *F*, a pawl *L* normally in engagement with the opening *i* in the slide *E*, a spring *H*, connecting the pawl *G* with the operating-slide *E*, and a spring *I*, for retracting the delivery-slide *F*.
- 40 6. In a vending-machine in which the de-

livery and operating slides are connected by means of a coin, the combination, with said slides and a suitable coin-holder, of a pawl 60 or dog adapted to engage the delivery-slide and a second pawl or dog connected with the first and adapted to engage the operating-slide.

7. In an automatic vending-machine in 65 which the delivery and operating slides are connected by means of a coin, the combination, with said slides and a suitable coin-holder, of the pawls or dogs *G* and *L*, adapted to automatically engage, respectively, the delivery and operating slides.

8. In a vending-machine, the combination, with the slide *E*, provided with the opening *i* and the teeth or projections *j*, of a rocking pawl *G*, a spring *H*, connecting the pawl and 75 the slide *E*, a delivery-slide *F*, a spring-eye connecting said slide with the fixed part of the machine, and a pawl *L*, secured to the pawl *G* and adapted to engage the opening *i*.

9. In a vending-machine, the combination, 80 with a delivery-slide and an operating-slide, of a double pawl, such as *G L*, adapted to engage alternately the slides *E* and *F*.

10. In a vending-machine, the combination, with a slide *E*, provided with a coin-slot *e*, of 85 an arm or finger *K*, secured to the under side of said slide with its front end in line with the rear wall of said slot *e*, a delivery-slide *F*, provided with a stud or projection *g* normally in advance of the coin-slot *e*, and blocks 90 or supports for the sides of the coin.

11. In an automatic vending-machine, the supporting-blocks *M* for the coin, provided with flanges *k l*, having reversely-curved faces.

12. In a vending-machine, the combination, 95 with the guides *D D* and the slides *E F*, of the blocks *M M*, secured to the guides *D D*, and each provided with flanges *k l*, the flanges *k* curving inward toward each other at their lower ends, and the flanges *l* curving inward 100 toward each other at their upper ends.

13. In a vending-machine, the combination, with a slide *E*, provided with a coin-slot and with a delivery-slide *F*, provided with a stud or projection *g*, of supports for the sides of 105 the coin, and an arm or finger *K*, secured to the under side of the slide *E* and adapted to bear at the center approximately of the coin.

In witness whereof I hereunto set my hand in the presence of two witnesses.

JOHN A. WILLIAMS.
